(57) **CLAIM**

The ornamental design for a hand-operated instrument and tool for laboratories as shown and described.

DESCRIPTION

The patent or application file contains at least one drawing executed in color. Copies of this patent or patent application publication with color drawing(s) will be provided by the Office upon request and payment of the necessary fee.

1. Hand-operated instrument and tool for laboratories
2. Hand-operated instrument and tool for laboratories

The characteristic features of the design lie in the combination of the shape of the laboratory instrument as shown; it is a rectangular laboratory instrument with rounded edges and two viewing windows, right and left, and a glass door at the front; a long handle is attached to the bottom of the glass door, which can be used to open the door; inside the design, a robotic arm can be seen at the top left, which can be moved to the right via the rail attached to the inside in the rear part of the instrument; the outer lower part of the laboratory

(Continued)

instrument is surrounded by a dark-colored strip, which makes up approx. $\frac{1}{3}$ of the height of the instrument. The portions of the hand-operated instrument and tool for laboratories shown in broken lines form no part of the claimed design.
